ELECTRIC HORN

Jay J. Reinhart, Farmington Hills, Mich., assignor to
Sparton Corporation, Jackson, Mich.

Filed Oct. 31, 1974, Ser. No. 519,509

Term of patent 14 years

Int. Cl. D10—06

U.S. Cl. D10—120

FIG. 1

FIG. 2

FIG. 3

FIG. 4

FIG. 5

FIG. 1 is an elevational view of an electric horn in accord with my new design as taken from the left side thereof, the right side being the mirror image thereof,

FIG. 2 is a top plan view of my new design,

FIG. 3 is a bottom view of the design,

FIG. 4 is a front elevational view, and

FIG. 5 is a rear elevational view of my new electric horn design.

I claim:

The ornamental design of an electric horn, substantially as shown.
